UNITED STATES PATENT OFFICE.

GEORGE L. BENNETT, OF CLEVELAND HEIGHTS, OHIO.

ICE BOX.

Application filed May 6, 1924. Serial No. 711,314.

My invention relates to ice boxes, and more particularly to an ice box in which a large supply of ice may be stored in a manner that will have no effect in cooling articles in the refrigerator, means being provided whereby a portion of the ice thus being stored may be separated from the remainder and delivered to an icing compartment where air will circulate about same and throughout the refrigerating chambers, so as to preserve the contents of the ice box.

Heretofore, in small ice boxes or refrigerators, a single icing compartment has been provided, the capacity of this compartment being proportioned to the size of that of the ice box or refrigerator. In such ice boxes the entire contents of the ice box was exposed to the relatively higher temperatures of the air throughout the ice box and to still warmer air each time that access was had to the ice box.

From the standpoint of the economical distribution of ice by the manufacturer or dealer, such ice boxes involve considerable expense, owing to the necessity for frequent icings in small quantities. Furthermore, in such ice boxes, cake ice only could be used.

In an ice box embodying my invention, I provide an icing compartment in communication with other parts of the ice box or refrigerator so as to have the usual effect of causing ice therein to bring all parts of the refrigerator to the desired low temperature well above the freezing point of water, and also a storage chamber normally sealed in relation to said ice compartment, but capable of being placed in communication therewith in a manner to permit the housewife to ice the ice compartment from said storage chamber.

The storage chamber may be so formed as to receive either broken ice or cake ice, a mechanism being provided whereby, when the desired bulk of ice has been delivered to the ice compartment from the storage chamber, the ice so delivered may be separated from any remaining ice in the storage chamber as an incident to the closing of the means of communication between said chamber and said compartment.

The construction of the ice box of my invention is such that the ice within the storage chamber will not be subject to the action of circulating air, thus materially reducing the shrinkage of this ice through melting, the storage conditions being similar to those

of the ice in an ordinary ice house, and the loss through shrinkage being little greater than that which is incident to the storage of ice in such houses.

To avoid likelihood of the gate closing the communicating passage between the ice storage chamber and the icing compartment being accidentally left open, I preferably provide automatic closure means for said gate which, however, will become operative only after there has been an effective separation of a portion of the ice and its delivery to the icing compartment.

The invention consists primarily in an ice box embodying therein suitable storage chambers for provisions, an icing compartment for maintaining the desired low temperature in said chambers, a storage chamber of relatively greater capacity than said icing compartment and positioned above same, means forming a passageway by which said storage chamber communicates with said icing compartment, a slidable gate adapted to close said passageway, and separate ice delivered to said icing compartment from that contained in said chamber, and means actuating said gate; and in such other novel features of construction and combination of parts as are hereinafter set forth and described, and more particularly pointed out in the claims hereto appended.

Referring to the drawings,

Fig. 1 is a vertical section through an ice box adapted to receive broken ice, embodying my invention;

Fig. 2 is a similar view showing the construction of the ice storage chamber to adapt it for the receipt of cake ice, and the cleavage of cakes so as to permit a portion only of the cakes to be delivered to the icing compartment;

Fig. 3 is a detail view of the hand wheel for actuating the gate closing the passage between the storage chamber and the icing compartment;

Fig. 4 is a detail view of the gate used in Fig. 2; and

Fig. 5 is a fragmentary, cross-section of the upper part of the ice box shown in Fig. 2, illustrating the ratchet spring construction for preventing movement of an ice cake or cakes with the gate after an entire cake of ice has passed from the storage chamber to the icing compartment.

Like letters refer to like parts throughout the several views.

In the embodiment of my invention shown in the drawings, *a* indicates the housing of an ice box or refrigerator of the usual and well known insulated construction, and provided with any desired arrangement of provision chambers *b* toward the bottom of the housing. Communicating with said chambers *b* is an icing compartment *c* which may be so constructed as to be adapted to receive either broken ice, as shown in Fig. 1, or piece ice, as shown in Fig. 2. This compartment *c* is arranged adjacent the provision chambers *b* in the usual manner, and is of a capacity to maintain the desired low temperature within these chambers.

At *d* I have shown in dotted lines, an ordinary drain pipe leading from the compartment *c*.

Above the uppermost chamber *b* and the icing compartment *c* is a partition *e* having an opening therethrough at *f* through which ice may enter the compartment *c* from above.

The partition *e* has a slideway formed therein at *e'* adapted to receive a cut-off gate *g*, the edge of which presented toward the opening *f* is equipped with a shearing blade consisting of a bevel for reducing the edge thereof to what may be termed a knife edge, either with or without spikes for separating or cleaving a body of ice in the path of movement of this gate *g* while lifting the portion of said ice from within the gateway to within the storage chamber.

The partition *e* forms a storage chamber *h* in the upper part of the housing *a*, which chamber may be placed in communication with the icing compartment *c* through the opening *f* by the movement of the gate *g*. If this chamber *h* is to receive broken ice, it will have converging bottom walls as shown more particularly in Fig. 1, while if it is designed to receive cake ice, the partition *e* will form the bottom of this chamber so as to permit the utilization of the gate *g* for successively moving cakes of ice in relation to the opening *f* with the gradual exhaustion of the supply of ice in this chamber *h*.

The top of the housing *a* is closed in any desired manner, as by the hinged top *i*, for the purpose of facilitating the charging of either broken or cake ice to within the storage chamber *h*.

The partition *e* at one side of the opening *f* has a socket therein adapted to receive the sliding gate *g* and seated within this socket and acting against said gate are compression springs *j* having a normal tendency to close the gate, and capable of completing the closure of the gate in the event of a temporary clogging thereof by a small piece of ice at the forward jamb for this gate indicated at *e*².

The gate *g* is provided on the underside thereof with a rack *k* co-operating with a

pinion *k'* carried by a shaft extending beyond the front wall of the housing *a* and having secured thereto a hand wheel *m* by means of which the gate may be actuated against the tension of the spring *j*. Preferably I provide the shaft carrying the pinion *k'* and wheel *m* with a finger *n* which will co-operate with gauge marks upon the front of the ice box so as to indicate whether the gate is open or closed.

In the form of the invention shown in Fig. 2, the forward edge of the gate *g* is provided with stiletto picks *o* for causing cleavage of a piece of ice from a larger cake. In this form of the invention, where the one or more cakes of ice rest upon the gate *g*, there is likelihood of the opening movement of this gate causing a movement of the cake of ice immediately above the opening *f*, away from said opening. To correct this condition, I provide the flat spring ratchets *p* secured to the side walls of the storage chamber *h* and in engaging relation with the sides of the cake of ice, thus restraining movement thereof with said gate.

In using an ice box of my invention, the conditions will be substantially as follows:—

Referring to the form of the invention shown in Fig. 1, broken ice is delivered to within the storage chamber *h* through the open top thereof until this chamber is filled. When the top is closed, there will be no circulation of air in this compartment, so that shrinkage through melting of ice will be reduced to a minimum. Under normal conditions the passage *f* is closed by the gate *g*. When it is desired to fill the icing compartment *c*, or replenish the supply of ice in that compartment, it is merely necessary to use the hand wheel *m* to impart movement to the gate within the socket in the partition *e* against the tension of the spring *j*, thus permitting the ice to enter the compartment *c* until this compartment is completely filled. When the compartment is filled, the hand wheel *m* is used to reverse the movement of the gate *g* assisted by the spring or springs *j*, the forward knife edge of said gate cleaving its way through the mass of ice and raising a portion thereof above the gate so as to restore it to within the chamber *h*. In the event of an incomplete closure of the gate, by reason of its obstruction by a small piece of ice, the spring *j* will continue to act in a manner to ensure the complete closing of the gate as the ice melts, or is moved from its position.

The finger *n* will indicate to the operator whether the gate is open or closed, and thus minimize likelihood of air at the higher temperature existing within the ice box, entering the storage chamber *h*.

In the form of the invention shown in Fig. 2, the conditions are the same as heretofore described, with the exception that

cake ice is used instead of broken ice, so that as the gate *g* is opened, a cake of ice will descend through the opening *f* to the fullest extent permitted by the clearance in this chamber. Hence under some conditions a cake of ice will extend across the opening *f* in the path of movement of the gate *g*, in which event the picks *o* will cut the ice with a clear line of cleavage, the bevelled end of the gate

10 raising the portion of the cake remaining above the gate to within the chamber *h*.

Since one or more cakes of ice will rest upon the gate *g* within the chamber *h*, the closing movement of the gate will always 15 position a cake or a part of a cake above the passage *f* where it may descend to within the icing compartment *c*. The ratchet springs *p* will prevent movement of a cake of ice with the gate *g* during the opening movement of said gate.

By means of an ice box embodying my invention, I am enabled to secure not only economy by reason of the saving of labor due to the requirement for but infrequent 25 filling of the storage chamber *h*, but also economy to the extent that the compartment *c* may always be filled to approximately its maximum capacity and thus secure at all times the effective chilling of the air within 30 the ice box and avoid that loss due to the rise of temperature in a box resulting from insufficient volume of ice in the icing compartment.

It is apparent that the detailed construction of the housing *a* is immaterial to the invention, and that the details of construction shown in the accompanying drawings may be widely varied without departing from the spirit and scope of the invention.

Having described the invention, what I claim as new and desire to have protected by Letters Patent, is:—

1. An ice box embodying therein suitable storage chambers for provisions, an icing compartment for maintaining the desired low temperature in said chambers, a storage chamber for ice of relatively greater capacity than said icing compartment and positioned above same, means forming a passageway by which said last named storage chamber communicates with said icing compartment, a slidable gate adapted to close said passageway, and separate ice delivered to said icing compartment from that contained in said storage chamber for ice, and means actuating said gate.

2. An ice box embodying therein suitable storage chambers for provisions, an icing compartment for maintaining the desired low temperature in said chambers, a storage chamber for ice of relatively greater capacity than said icing compartment and positioned above same, a partition between said icing compartment and said last named storage chamber having a passageway by which

said storage chamber for ice communicates with said icing compartment, a slideway in said partition, a gate mounted in said slideway having a bevelled forward edge, said gate being adapted to close said passageway, and separate ice delivered to said icing compartment from that contained in said storage chamber for ice, and means actuating said gate.

3. An ice box embodying therein suitable storage chambers for provisions, an icing compartment for maintaining the desired low temperature in said chambers, a storage chamber for ice of relatively larger capacity than said icing compartment and positioned above same, a partition between said icing compartment and said last named storage chamber having a passageway by which said storage chamber for ice communicates with said icing compartment, a slideway in said partition, a gate mounted in said slideway having a bevelled forward edge, said gate being adapted to close said passageway, and separate ice delivered to said icing compartment from that contained in said storage chamber for ice, and means actuating said gate.

4. An ice box embodying therein suitable storage chambers for provisions, an icing compartment for maintaining the desired low temperature in said chambers, a storage chamber for ice of relatively greater capacity than said icing compartment and positioned above same, means forming a passageway by which said last named storage chamber communicates with said icing compartment, a slidable gate adapted to close said passageway, and separate ice delivered to said icing compartment from that contained in said storage chamber for ice, a rack carried by said gate, a pinion meshing with said rack and means exposed exteriorly of the ice box whereby said pinion may be rotated to either open or close said gate.

5. An ice box embodying therein suitable storage chambers for provisions, an icing compartment for maintaining the desired low temperature in said chambers, a storage chamber for ice of relatively greater capacity than said icing compartment and positioned above same, a partition between said icing compartment and said last named storage chamber having a passageway by which said storage chamber for ice communicates with said icing compartment, a slideway in said partition, a gate mounted in said slideway having a bevelled forward edge, said gate being adapted to close said passageway, and separate ice delivered to said icing compartment from that contained in said storage chamber for ice, springs acting upon said gate to normally close same, a rack carried by said gate, a pinion mesh-

ing with said rack and means exposed exteriorly of the ice box whereby said pinion may be rotated to either open or close said gate.

5 6. An ice box embodying therein suitable storage chambers for provisions, an icing compartment for maintaining the desired low temperature in said chambers, a storage chamber for ice of relatively greater capacity than said icing compartment and positioned above same, means forming a passageway by which said last named storage chamber communicates with said icing compartment, means forming an inclined bottom to said storage chamber, whereby broken ice is directed towards said passageway, a 10 slideable gate adapted to close said passageway, and separate ice delivered to said icing compartment from that contained in said storage chamber for ice, and means actuating said gate.

7. An ice box embodying therein suitable storage chambers for provisions, an icing compartment for maintaining the desired low temperature in said chambers, a storage chamber for ice of relatively greater capacity than said icing compartment and positioned above same, a partition between said icing compartment and said last named storage chamber having a passageway by which said storage chamber for ice communicates with said icing compartment, a slideway in said partition, means forming an inclined bottom to said storage chamber, whereby broken ice is directed towards said passageway, a gate mounted in said slideway hav-

ing a bevelled forward edge, said gate being adapted to close said passageway, and separate ice delivered to said icing compartment from that contained in said storage 40 chamber for ice, and means actuating said gate.

8. An ice box embodying therein suitable storage chambers for provisions, an icing compartment for maintaining the desired low temperature in said chambers, a storage chamber for ice of relatively greater capacity than said icing compartment and positioned above same, a partition between said icing compartment and said last named storage chamber having a passageway by which said storage chamber for ice communicates with said icing compartment, a slideway in said partition, means forming an inclined bottom to said storage chamber 50 for ice, whereby broken ice is directed towards said passageway, a gate mounted in said slideway having a bevelled forward edge, said gate being adapted to close said passageway, and separate ice delivered to said icing compartment from that contained in said storage chamber for ice, springs acting upon said gate to normally close same, a rack carried by said gate, a pinion meshing with said rack and means exposed exteriorly of the ice box whereby said pinion may be rotated to either open or close said gate.

In witness whereof I have hereunto affixed my signature this 12th day of April, 1924.

GEORGE L. BENNETT.
